UNITED STATES PATENT OFFICE.

RICHARD GREENLEAF TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

SHUTTLE PLACER.

Application filed November 6, 1924. Serial No. 748,249.

This invention relates to shuttle placers for looms and more particularly to that style of placer which is actuated by direct contact with a misplaced shuttle.

5 In my co-pending application, Serial No. 741,034 I have shown a type of shuttle placer comprising a roll positioned to engage a misplaced shuttle and movable laterally by a slightly misplaced shuttle to locking position. The mechanism set forth therein provides a fixed unyielding stop for the shuttle placer when the same has been moved laterally and I have found that under certain 10 conditions this construction results in a harsh and abrupt action. This is especially true with certain shapes of shuttles when the binder pressure is excessive.

It is the principal object of my present invention to provide a shuttle placer normally yieldable against relatively light pressure but movable laterally into operative relationship with a slide yieldable under relatively high pressures when engaged by a slightly misplaced shuttle.

20 25 A further object of my invention is to provide a shuttle placer and a sliding carrier therefor which shall be given a normal rearward movement toward the shuttle and also a lateral movement to hold the same in normal position by a single resilient means.

With these and other objects in view which will appear as the description proceeds, my invention resides in the combination and arrangement of parts hereinafter described 30 and set forth in the claims.

35 In the accompanying drawings wherein I have shown one form of my invention,

Fig. 1 is a top plan view of a portion of a loom having my invention applied thereto and showing the same in normal position with a properly placed shuttle on front center,

40 45 Fig. 2 is a view similar to Fig. 1 but showing the shuttle placer being moved forwardly to stop the loom by a widely misplaced shuttle,

Fig. 3 is a view similar to Fig. 1 but showing the placer moved laterally by a slightly misplaced shuttle and in position to place the 50 same, and

Fig. 4 is a vertical section on line 4—4 of Fig. 1.

Referring more particularly to the drawings it will be seen that I have provided a

breast beam 10 having extending therefrom 55 a knock-off stand 11 and having a slot 12 therein which is formed with a notch 13. Shipper handle 14 is normally retained in notch 13 when the loom is running. Lying immediately in front of the shipper handle is 60 arm 15 of lever 16 pivoted to the stand as at 17. The other arm 18 of the lever 16 is formed with a barrel 19 in which is slidably mounted a plunger 20 pressed normally to the right as seen in Fig. 1 by spring 21 and 65 limited in its motion by cotter pin 22.

A stand 23 is bolted or otherwise secured to the breast beam and has a guide 24 thereon for the side filling stop motion slide 25, the forward end of which is operatively positioned to engage the barrel 19 and swing the lever 16 about the center thereof to stop the loom when a fault in the filling occurs. Upstanding from the stand 23 on the rear side thereof is a boss 26 having a threaded bore 70 75 27 which receives the threaded head 28 of a stud 29 and the forward end of said stand has formed integrally therewith a second boss 30 which is drilled to receive the forward reduced shank 31 of the stud 29. Set screw 32 is provided to hold any adjusted setting of the head 28 with respect to the stand. Surrounding the shank 31 is a heavy coil spring 33 the forward end of which pushes against boss 30 and the rear end of 80 85 which forces arm 34 of slide 35 against the head 28. The forward end of slide 35 is preferably so proportioned as to have sliding contact with the right hand side of the boss 30.

80 Formed integral with the stand 23 is a wall 36 which together with slide 35 forms a guideway in which is located a sliding carrier 37 positioned for engagement with the plunger 20 when moved forwardly. Said carrier 37 has pivotally mounted on the rear end thereof a head 38 on which is rotatably mounted the shuttle placer roll 39. The body of the carrier 37 may be hollow and the rear end thereof is provided with a pocket 40 100 which receives one end of a guide rod 41. The forward end of said rod passes loosely through a guide bearing 42 formed on the stand 23, and also passes through the front wall of the carrier 37, being held in fixed position with respect to the carrier by means of set screw 43. A light coil spring 44 surrounding the rod 41 is located between the 105

boss 42 and the rear portion of the carrier 37 and serves to hold the carrier and placer roll normally in rear position. A stop lug 45 extends laterally from the carrier 37 and is 5 positioned for engagement with the front portion of wall 36.

One of the vertical walls of the carrier 37 is provided with a notch 46 which under normal conditions is out of alignment with the 10 rear end of slide 35. As shown herein the inner faces of slide 35 and the wall 36 are slightly oblique, being somewhat farther apart at their rear ends than at their forward ends. The forward end of these walls 15 serves as a guide for the front end of carrier 37, the carrier being movable angularly about the boss 42 so that the rear end of carrier 37 may be moved laterally from its normal position in contact with wall 36 to engaging position with movable wall 35. The lug 45 is out of line with the rod 41 and spring 44 serves normally to hold the carrier in the position shown in Fig. 1 with the notch 46 out of alignment with the slide 35. 20 A cover 47 may be provided to restrain upward movement of the carrier 37.

Under normal conditions the heavy spring 33 will hold the arm 34 against the head 28 and thus place the slide 35 in rearmost position and light spring 44 will hold the lug 45 against the wall 36 so that the carrier 37 will lie against said wall 36. Roll 39 under these conditions will be so placed as to be 25 out of contact with shuttle S when properly placed but should said roll engage a widely misplaced shuttle as indicated in Fig. 2 the roll and carrier therefor will move forwardly against the light pressure of spring 44 and swing lever 16 about the pivot there- 30 of to stop the loom. However, if the roll 39 should engage the rounded end of a slightly misplaced shuttle as indicated in Fig. 3 it will roll along said rounded surface and move the carrier 37 laterally until 35 the same is in contact with the slide 35 and notch 46 is in line with the slide 35. If the shuttle does not stick and can be placed without excessive pressure the notch 46 will engage the rear end of slide 35 and the 40 placer and carrier will be held against further forward motion, the roll 39 rotating on its center and pushing the shuttle into its box. Should the shuttle stick in the box or for any other reason resist placing the spring 44 will yield and the carrier 37 will move 45 forwardly to engage the plunger 20 and stop the loom.

Thus it will be seen that the carrier is 50 movable forwardly from either of its lateral positions to stop the loom. By means of screw head 28 the relative position of slide 35 with respect to the notch 46 may be changed as desired.

From the foregoing it will be seen that I 55 have provided a shuttle placer actuatable by a

misplaced shuttle and so arranged as to assume one or the other of two lateral positions from either of which it can move to stop the loom. Also, the placer is called upon to act against two springs of different 60 strengths one of which is relatively light to permit forward movement of the placer when the latter is opposite a widely misplaced shuttle and the other of which is relatively strong to require the placer to move 65 the shuttle under ordinary conditions but which will yield to stop the loom when resistance of the shuttle is abnormal. Furthermore, it will be seen that the single light spring 44 suffices to move the carrier 70 37 against the wall 36 through the engagement of the lug 45 with said wall 36.

Having thus described my invention it will be apparent that changes and modifications may be made therein by those skilled 75 in the art without departing from the spirit and scope of the invention, and I do not wish to be limited to the details herein disclosed, but what I claim is:

1. In a loom, a shuttle placer, means to 80 offer relatively weak yielding resistance to the movement of the placer when the latter engages a widely misplaced shuttle, and means to offer relatively heavy yielding resistance to said shuttle placer when the lat- 85 ter engages a slightly misplaced shuttle.

2. In a loom, a shuttle placer, two independent means each effective to offer yielding resistance to the placer, said placer being resisted by one of said means when en- 90 gaging a widely misplaced shuttle and by both of said means when engaging a slightly misplaced shuttle.

3. In a loom, a shuttle placer, a carrier therefor, a guide for the carrier, and two re- 95 silient devices of different strengths, the carrier normally being in position to be moved against one of said resilient devices and being movable into position to be resisted by both of said devices when engaged by a mis- 100 placed shuttle.

4. In a loom, a shuttle placer movable laterally when engaged by a slightly misplaced shuttle, a carrier therefor, a relatively light spring normally resisting forward move- 105 ment of the carrier, a relatively heavy spring, and means to establish connections between the carrier and said heavy spring when the carrier is moved laterally by en- 110 gagement of the placer with a slightly mis- 115 placed shuttle.

5. In a loom, a shuttle placer, a carrier therefor, a spring holding said carrier and placer in normal position, a resilient device located adjacent to but out of the path of 120 the carrier when the latter is moved by a widely misplaced shuttle, and means formed on said carrier and resilient device to be interengaged and effective to resist forward motion of the carrier by said resilient means 125

when said carrier is engaged by a slightly misplaced shuttle.

6. In a loom, a shuttle placer movable laterally by a slightly misplaced shuttle, a carrier therefor, guiding walls for said carrier, means to hold said carrier normally and yieldingly in position to be moved relatively to said walls when engaged by a widely misplaced shuttle, one of said walls being yieldingly mounted to move with the carrier, and means on the carrier movable into engagement with the movable wall when the carrier is moved laterally by a misplaced shuttle to cause said carrier to be opposed by the action of said wall when the placer is moved laterally.

7. In a loom, a shuttle placer movable laterally by engagement with a slightly misplaced shuttle, spaced walls to guide said placer, one of said walls being fixed and the other wall being movable against relatively heavy pressure, and means to hold said placer normally against the fixed wall, the placer being movable against the action of said means into position to engage the movable wall when moved laterally by a slightly misplaced shuttle.

8. In a loom, a shuttle placer movable laterally by and receiving a shuttle placing movement from a misplaced shuttle, a carrier for said placer, guiding walls for said carrier, one of said walls being fixed and the other being movable, relatively light yielding means to hold said carrier in rear position and against said fixed wall, relatively heavy yielding means to resist movement of said movable wall, and means to establish

connection between said carrier and the movable wall when the shuttle placer engages a misplaced shuttle and is moved laterally thereby.

9. In a loom, a shuttle placer normally at rest and having a shuttle placing movement when engaged by a slightly misplaced shuttle, guiding walls for said placer, means to yieldingly mount one of said walls for forward movement, and interengaging means between said wall and the placer, said placer being movable forwardly when engaged by a widely misplaced shuttle without establishing connection with said wall and being movable laterally when engaged by a slightly misplaced shuttle to establish connection with said movable wall.

10. In a loom, a shuttle placer normally inactive when the shuttle is properly placed, means to offer relatively weak yielding resistance to the movement of the placer when the latter engages a widely misplaced shuttle, and means to offer relatively heavy yielding resistance to said shuttle placer when the latter engages a slightly misplaced shuttle.

11. In a loom, a shuttle placer normally inactive when the shuttle is properly placed, two independent means to offer yielding resistance to the placer, said placer being resisted by one of said means when engaging a widely misplaced shuttle and by both of said means when engaging a slightly misplaced shuttle.

In testimony whereof I have hereunto affixed my signature.

RICHARD GREENLEAF TURNER.
